UNITED STATES PATENT OFFICE

FRANK W. TUCKER, OF NEW YORK, N. Y.

COIN-CONTROLLED VENDING-MACHINE.

1,054,153.

Specification of Letters Patent. Patented Feb. 25, 1913.

Application filed May 31, 1912. Serial No. 700,611.

To all whom it may concern:

Be it known that I, FRANK W. TUCKER, a citizen of the United States, and resident of the city of New York, in the county of 5 New York and State of New York, have invented certain new and useful Improvements in Coin-Controlled Vending-Machines, of which the following is a specification.

10 The present invention relates to a coin controlled vending machine or apparatus which delivers automatically small wares, such as chewing gum, chocolate and other confections upon passing a proper coin into 15 the machine by a purchaser.

One of the objects of the invention is to provide a compact, efficient, reliable and comparatively inexpensive machine of this character.

20 Another object of the invention is to provide a vending machine with a simple and efficient device for preventing fraud against the apparatus, such fraud preventing device rejecting checks or coins of improper 25 size and material.

With these and other objects in view, which will more fully appear as the nature of the invention is better understood, the same consists in the combination, arrangement and construction of parts hereinafter 30 fully described, pointed out in the appended claims and illustrated in the accompanying drawings, it being understood that many changes may be made in the size and proportion 35 of the several parts and minor details of construction without departing from the spirit or sacrificing any of the advantages of the invention.

One of the many possible embodiments of 40 the invention is illustrated in the accompanying drawings, in which:—

Figure 1 is a front elevation of an apparatus constructed in accordance with the present invention; Fig. 2 is a side elevation 45 thereof; Fig. 3 is a section taken on line 3—3 of Fig. 1; Fig. 4 is a section taken on line 4—4 of Fig. 1; Fig. 5 is a front elevation of the device with the cover removed; Fig. 6 is a section taken on line 6—6 of Fig. 50 5; Fig. 7 is a rear elevation of the cover of the apparatus with the operating parts thereon; Fig. 8 is a front elevation of a detail of construction; and Fig. 9 is a plan view of another detail.

55 In the drawings, the numeral 10 indicates a suitable casing, preferably made of metal,

and attached to a support 11, such as the back of a chair, in any suitable manner. Over this casing fits a cover 12, held upon the casing in a manner hereinafter to be described. In one side of the cover are provided a plurality of apertures 13, 13, registering with apertures 14, 14 in the corresponding side of the casing 10, the apertures 13 being covered by a glass plate 15, whereby the quantity of the goods contained in the casing can be ascertained without opening the same. The goods-box or holder 16 is a frame-like structure, which is held to the inside of the casing 10 by means of rivets 17, 17 or otherwise, said goods-box comprising two vertical sides 18 and 18', and a bottom 19, the width of the latter being smaller than the distance between the sides 18 and 18'. To the side 18' is pivoted 70 at 20 a slat 21, the length of which corresponds substantially to that of the side 18'. This slat is arranged in a plane at right angles to its corresponding side of the goods-holder. A spring 22 is attached to 75 the side 18' and extends below the lower edge thereof. When the slat 21 is turned around its pivot into a substantially horizontal plane, the goods-box may be filled with chewing gum, chocolate or other confections 23. Upon the top of the goods is placed a weight 24, after which the slat 21 is returned to its normal vertical position, overlapping thereby a substantial portion 80 of the goods and holding them thus in their compartment. The weight 24 is provided with a projection 25, which travels, as the goods are delivered from the apparatus, in the space formed between the side 18 of the goods-box and that side of the casing 10 85 which is provided with the apertures 14 above referred to.

Below the bottom 19 of the goods-box is located a coin receptacle 26, provided with a removable front 27. In this coin receptacle is arranged a lock 28, its key-hole being accessible through an opening 29 in the bottom 30 of the casing 10, and through a registering opening in the cover 12. The bolt 31 of this lock is adapted to be projected through an opening in the side of the coin receptacle into an opening 32 in a substantially vertical partition 33 of the cover 12. This partition extends upwardly a distance which corresponds to the height of the coin receptacle. The top 34 of the cover carries a plurality of pins 35, adapted to be

seated in recesses 36 in the support 11. When the pins are seated in their recesses and when the bolt of the lock 28 is shot into the opening in the partition 33 of the cover, the apparatus will be safely kept closed.

The coin paid for a piece of goods is placed into a slot 37 in a mouth piece 38, which is either formed integral with or attached to the cover 12, and passes thence into a chute 39 stamped into the cover, and thence into a vertical passage 40, which is formed between the front portion 41 of the cover 12 and a suitably bent strip 42, hinged at 43, 43 to a supporting plate 44, the latter being attached by means of screws 45, 45, or otherwise, to the innerside of the front 41 of the cover of the apparatus. The edge 42' of the strip 42 is kept against the front 41 of the cover 12 by means of a spring 42''. The passage 40 is provided near its bottom with an inclined rebound plate 46, onto which the coin drops in its downward movement. In striking the rebound plate 46, the coin is deviated from its course, springing back at the same angle at which it strikes the rebound plate 46 toward a swinging arm 47, which is pivoted at 47' to the innerside of the supporting plate 44, and, if the coin is of the proper weight and of other physical properties which will be hereinafter mentioned, it will cause the arm 47 to swing toward that side of the casing which is provided with the apertures 14, and permit thereby the coin to fall onto a delivery mechanism 48. This delivery mechanism consists of a coin lever 49, pivoted at 50 to a disk segment 51, which in turn is pivoted at 52 to the cover 12, said disk segment being arranged in a circular depression 53 in said cover. A knob 54 is attached to the disk segment, and projects through an arc-shaped slot 55 in the cover 12 of the casing. The outer end of the coin lever 49 carries a pin 56, which will abut against a horizontal extension 57 of the side 18 of the goods-box, when the coin lever is tripped by the weight of the coin resting thereon. In this position the pin 56 is arranged in the plane of the lowermost of the stack of goods in the goods-box, and when the disk segment 51 is shifted by actuating the knob 54, it will cause one piece of the goods to fall onto a guard plate 58, which is fulcrumed at 59 to one of the sides 55 of the casing 10 and the side of the coin box 26. In dropping onto this guard plate, the piece of goods will tilt the plate in the direction of the arrow shown in Fig. 4 of the drawings, and fall thus into a tray 60 at the bottom of the casing 10, to be taken out of the apparatus through an opening 61 in the cover above the plane of the tray 60.

The guard plate 58, being arranged a substantial distance above the opening 61, ad-

mits the buyer's fingers into the tray to draw out conveniently the delivered piece of goods. It prevents, however, persons passing either their hands or implements upward into the apparatus for the purpose of tampering with the interior mechanism of the same.

A further fraud preventing device consists of a magnet 62, which is attached to the supporting plate 44, its poles being arranged in close proximity to the passage 40, and serving to prevent such checks from acting upon the coin lever 49 which are susceptible to magnetic attraction. The mode of operation of this magnet will be fully described hereinafter when the fraud preventing properties of the swinging arm 47 will be fully discussed.

As soon as all of the goods have been withdrawn from the apparatus, the projection 25 of the weight 24 will act upon the end 63 of a lever 64, which is fulcrumed at 65 to the supporting plate 44. The other end of this lever rests normally upon a pin 66, and supports thereby a bellcrank lever 67, which is pivoted at 68 to the supporting plate. The arm 69 of this lever is arranged at a distance from the swinging arm 47 to allow the latter to swing toward that side of the casing 10 which is provided with the apertures 14 a distance which will permit the coin, rebound by the plate 46, to drop onto the coin lever 49. The normal positions of the levers 64 and 67 are shown in dotted lines in Figs. 1, 7 and 8. When all of the goods are delivered from the apparatus, the projection 25 of the weight 24 forces the arm 63 of the lever 64 downward into the position shown in full lines in Fig. 8. By this operation, the bellcrank lever 67 is tilted into the position shown in full lines in Fig. 8, whereby its arm 69 is brought nearer the swinging arm 47. As, therefore, a coin is rebound against the swinging arm 47, this arm is not adapted to swing far enough to permit the coin to drop onto the coin lever 49, it will fall into the tray 60, wherefrom it can be removed by the intending purchaser. It will be seen thus that all coins will be returned to the intending purchaser if the machine is empty.

When the coin lever 49 is in its normal position (shown in dotted lines in Fig. 1 and in full lines in Fig. 7 of the drawings), the pin 56 thereof is arranged in the level of a downwardly extending projection 70 upon the bottom 19 of the goods-box. When, therefore, the knob 54 of the disk segment 51 is actuated without inserting a coin, the pin 56 will abut against the projection 70, preventing thereby the disk segment 51 from completing its movement. Before, however, the pin 56 abuts against the projection 70, the end 49' of the coin lever 49 will contact with a block 71, which

is fulcrumed at 72 to the lower end of the strip 42. When the end 49' of the coin lever contacts with the block 71 and the disk segment 51 is being further shifted, the strip 42 will be turned around its hinges; spurious coins or other checks, such as for instance buttons, etc., which owing to their size did not fall through the passage 40, will thus be released and drop into the tray 60. The spring 42" returns then the strip 42 to its normal position. It will be observed that by means of this arrangement it is made impossible to clog the passage leading to the coin lever, as persons who passed coins of improper size through the slot into the passage 40 will clear the passage as they shift the disk segment 51 by means of the knob 54.

The operation of this device is as follows: A coin, in this case one cent, is dropped through the slot into the passage 40, falling onto the rebound plate 46. The cent, made of copper, possesses a certain resiliency which is a property of its material. Owing to this resiliency, the rebound plate 46 will cause the coin to spring back under an angle which is equal to the angle of incidence on the rebound plate. The cent will thus be thrown, as it were, against the swinging arm 47. The distance between the swinging arm 47 and the rebound plate 46, the angle of inclination of the rebound plate, and the weight of the swinging arm 47 have been found, of course, by experiments. The weight of the arm 47 is such as to permit the cent to swing said arm 47 toward the bell-crank lever 67, whereby said cent will drop on the coin lever 49, and tilt the same into the position shown in dotted lines in Fig. 7 of the drawings. In actuating now by means of the knob 54 the coin lever, the pin 56 will cause the lowermost of the stack of goods to be dropped into the tray 60, to be removed therefrom in the manner above-mentioned.

When the piece of goods has been delivered, the coin lever will be tilted back into its normal position, whereby the coin which has been paid by the purchaser for a piece of goods will drop into the coin receptacle.

If a light-weight coin is placed into the slot of the machine, it will fall onto the rebound plate 46, but will be unable, owing to its light weight, to swing the arm 47 far enough to fall onto the coin lever 49. It will simply drop into the tray 60 to be removed by the intending purchaser. Even if by accident it should fall onto the coin lever 49, it will be unable to tilt the latter to its operating position. It will be caused to fall into the coin receptacle when the next proper coin is passed into the machine. It has been found, however, that it occurs very seldom that a light-weight coin falls on the coin lever.

If a check which is susceptible to magnetic attraction is placed into the slot of the machine, the magnet 62 will act upon it, deviate it from its regular course in such a manner that its rebound upon the plate 46 will not be sufficient to swing the arm 47 the proper distance, so that it will simply be delivered into the tray 60, even if it were of the proper size, weight and resiliency.

Coins which are of the proper size and weight, but do not possess the resiliency of the material of a cent will never reach the coin lever, owing to the fact that their rebound is not sufficient to throw the arm 47. They will also fall into the tray 60.

From the foregoing it will be observed that, in order to operate the machine, a check must be provided, the size, weight and resiliency of which are in all respects identical with that of a cent. Any coins or checks which lack any one of these three properties cannot actuate the delivery mechanism of the apparatus.

What I claim is:

1. In a coin operated vending machine, the combination with a casing having a slot for the insertion of a coin and a downwardly extending passage leading therefrom, of a rebound plate in said passage, a tilting coin lever onto which the coin is adapted to be directed by said rebound plate, and a swinging arm against which the coin strikes as it passes from said rebound plate onto said coin lever.

2. In a coin operated vending machine, the combination with a casing having a slot for the insertion of a coin and a downwardly extending passage leading therefrom, of a rebound plate in said passage, a tilting coin lever onto which the coin is adapted to be directed by said rebound plate, a swinging arm against which the coin strikes as it passes from said rebound plate onto said coin lever, and means for preventing the full swing of said arm when all of the goods have been delivered from the machine.

3. In a coin operated vending machine, the combination with a casing having a slot for the insertion of a coin and a downwardly extending passage leading therefrom, of a rebound plate in said passage, a tilting coin lever onto which the coin is adapted to be directed by said rebound plate, a swinging arm against which the coin strikes as it passes from said rebound plate onto said coin lever, a lever fulcrumed to said casing, and means for tilting said lever so as to prevent the full swing of said arm when all of the goods have been delivered from the machine.

4. In a coin operated vending machine, the combination with a casing having a slot for the insertion of a coin and a downwardly extending passage leading therefrom, of a rebound plate in said passage, a

disk segment pivoted to said casing, a tilting coin lever carried by said disk segment onto which the coin is adapted to be directed by said rebound plate, and a swinging arm 5 against which the coin strikes as it passes from said rebound plate onto said coin lever.

5. In a coin operated vending machine, the combination with a casing having a slot 10 for the insertion of a coin and a downwardly extending passage leading therefrom, of a rebound plate in said passage, a disk segment pivoted to said casing, a tilting coin lever carried by said disk segment 15 onto which the coin is adapted to be directed by said rebound plate, a swinging arm against which the coin strikes as it passes from said rebound plate onto said coin lever, and means for preventing the 20 full swing of said arm when all of the goods have been delivered from the machine.

6. In a coin operated vending machine, the combination with a casing having a slot 25 for the insertion of a coin and a downwardly extending passage leading therefrom, of a rebound plate in said passage, a disk segment pivoted to said casing, a tilting coin lever carried by said disk segment 30 onto which the coin is adapted to be directed by said rebound plate, a swinging arm against which the coin strikes as it passes from said rebound plate onto said coin lever, a lever fulcrumed to said casing, 35 and means for tilting said lever so as to prevent the full swing of said arm when all of the goods have been delivered from the machine.

7. In a coin operated vending machine, 40 the combination with a casing having a slot, of a strip hinged to said casing forming a passage communicating with said slot, a rebound plate upon said strip in said passage, a disk segment pivoted to said casing, 45 a coin lever carried by said disk segment, and a swinging arm against which the coin strikes as it passes from said rebound plate onto said coin lever, said coin lever when no coin has passed onto it being adapted to 50 swing said strip around its hinge upon movement of said disk segment.

8. In a coin operated vending machine, the combination with a casing having a slot, 45 of a strip hinged to said casing forming a

passage communicating with said slot, a rebound plate upon said strip in said passage, 55 a disk segment pivoted to said casing, a coin lever carried by said disk segment, a swinging arm against which the coin strikes as it passes from said rebound plate onto said coin lever, said coin lever when no coin has passed onto it being adapted to swing 60 said strip around its hinge upon movement of said disk segment, and means for preventing the full swing of said arm when all 65 of the goods have been delivered from the machine.

9. In a coin operated vending machine, the combination with a casing having a slot, 70 of a strip hinged to said casing forming a passage communicating with said slot, a rebound plate upon said strip in said passage, 75 a disk segment pivoted to said casing, a coin lever carried by said disk segment, a swinging arm against which the coin strikes as it passes from said rebound plate onto 80 said coin lever, said coin lever when no coin has passed onto it being adapted to swing said strip around its hinge upon movement of said disk segment, a lever fulcrumed to said casing, and means for tilting said lever so as to prevent the full swing of said arm when all of the goods have been delivered from the machine.

10. In a coin operated vending machine, 85 the combination with a casing having a slot for the insertion of a coin and a downwardly extending passage leading therefrom, of a rebound plate in said passage, a tilting coin lever onto which the coin is 90 adapted to be directed by said rebound plate, a swinging arm against which the coin strikes as it passes from said rebound plate onto 95 said coin lever, a goods-box, a weight resting upon the top of the goods in said goods-box having a projection, a lever system adapted to be actuated by said projection for preventing the full swing of said arm when all of the goods have been delivered from the machine. 100

Signed at New York, in the county of New York, and State of New York, this 13th day of December, A. D. 1911.
